CLAIM

(**) Term: **14 Years**

The ornamental design for an air compressor enclosure for a reciprocating air compressor, as shown and described.

(21) Appl. No.: **29/146,961**

DESCRIPTION

(22) Filed: **Aug. 20, 2001**

FIG. 1 is a perspective view of an air compressor enclosure for a reciprocating air compressor embodying the invention.

(51) LOC (7) Cl. **15-02**

FIG. 2 is a front elevational view of an air compressor enclosure for a reciprocating air compressor of FIG. 1.

(52) U.S. Cl. **D15/7**

FIG. 3 is a top plan view of an air compressor enclosure for a reciprocating air compressor of FIG. 1.

(58) Field of Search D15/7-9; 417/234,

FIG. 4 is a right side elevational view of an air compressor enclosure for a reciprocating air compressor of FIG. 1.

417/229, 321, 410-411, 265, 415, 405,

FIG. 5 is a left side elevational view of an air compressor enclosure for a reciprocating air compressor of FIG. 1; and,

419

FIG. 6 is a rear elevational view of an air compressor enclosure for a reciprocating air compressor of FIG. 1.
